OTTO KARL REINHARDT, OF JAMAICA, NEW YORK, ASSIGNOR TO BOND ELECTRIC CORPORATION, A CORPORATION OF DELAWARE

TAMPING MACHINE

Application filed June 12, 1929. Serial No. 370,222.

This invention relates to tamping machines of the type employed in compacting the active material or carbonaceous mix about the carbon electrode in the manufacture of dry cells.

An object of this invention is generally to improve machines of the type mentioned and particularly to improve the feeding mechanism thereof, whereby the delivery of the carbonaceous material to the cell container is automatically and accurately controlled so that filling of the cells to a uniform height is assured.

Other objects and advantages of the invention will become apparent from the following description, taken in connection with the accompanying drawings, in which—

Figure 1 is a side view of the machine embodying this invention; Figure 2 is an enlarged fragmental front elevation of the machine; Figure 3 is a similar view of the rear of the machine; Figure 4 is a central vertical sectional view taken on line 4—4 of Figure 2, certain parts of the machine being shown in elevation for the sake of clearness; Figure 5 is an enlarged horizontal sectional view taken on line 5—5 of Figure 4; Figure 6 is a similar view taken on line 6—6 of Figure 4; Figure 7 is a vertical sectional view taken on line 7—7 of Figure 4; Figure 8 is an enlarged fragmental detailed view, partly in section and partly in elevation, showing the relation of the feeding mechanism to the automatically-actuated control mechanism for stopping the operation of such feeding mechanism as the latter moves downwardly during the tamping operation, and Figure 9 is a similar view showing the relation of the feeding mechanism to the automatically-actuated control mechanism at the instant of the completion of the tamping operation.

Referring to the drawings, the numeral 5 indicates a frame structure at the top of which is journalled at power shaft 6, carrying a pulley 7 adapted to be connected to a suitable source of power, not shown. To opposite ends of the shaft 6 are connected suitable cranks or wrist pins 8 and 9, to which are connected pitman rods 10 and 10', re-

spectively, adapted to actuate a tamping mechanism 11 and a feeding mechanism 12, the former being adapted to compact the active material or carbonaceous mix about the carbon electrode as such mix is delivered into the cell-container by the feeding mechanism. The tamping mechanism 11 is of a well-known type, heretofore employed in machines of this character, and includes a cross-head 13 connected to the pitman rod 10 and mounted to reciprocate within guides 14 secured to the side members of the frame 5. Carried by the cross-head 13 and rotatably mounted in the lower transverse member thereof, is a tamping head which includes a rotatable sleeve 16 to the lower end of which are secured a plurality of tamping fingers 17 adapted to enter the cell-container and there operate upon the mix to compact the same around the carbon electrode as such mix is delivered to the container by the feeding mechanism 12. To the upper end of the sleeve 16, is journalled an oscillatory pawl-actuating disc 18, carrying a finger 19 which is adapted to co-act with a stationary cam 20, secured to a suitable part of the frame 5. As the cross-head 13 is elevated the finger 19 moves over the face of the cam 20 so as to effect rotation of the disc in one direction, rotation of the disc in an opposite direction being effected, as the cross-head moves downwardly, by a tension spring 22, one end of which is anchored to a side member of the cross-head and the other end of which is connected to a pin 23 carried by the peripheral margin of the disc 18. Projecting from the disc 18 is an ear 24, carrying a pin 25 upon which is mounted a spring-pressed pawl 26, adapted to engage a ratchet wheel 27 secured to the upper end of the sleeve 16. From the pawl and ratchet mechanism just described, it will be apparent that as the cross-head 13 is reciprocated, the operation of the pawl-actuating disc 18 is such that the ratchet wheel 27, together with the sleeve 16, is intermittently rotated, with the result that the tamping fingers 17 carried by that sleeve are revolved about the carbon electrode, not shown, as the active material or mix is

tamped into a compact mass about such electrode.

For holding the carbon electrode centrally with respect to a cell-containee, there is provided a pair of yieldable gripping fingers 28, between which such electrode is inserted after each tamping operation. These fingers are carried by a vertically disposed finger-supporting stem 29, slidably mounted within a tubular bearing 30 upon which the sleeve 16 is adapted to slide, the bearing 30 being connected at its upper end to a suitable bracket 31 secured to the frame 5. Preferably a compression spring 32 is disposed within the sleeve 30 over the rod 29 to compensate for slight variations in length of the carbon electrodes, so that the lower ends of the carbon electrodes may be properly positioned with respect to the bottom of the cell-containee in every instance.

Located beneath the tamping head is a cell-containee support 34 in the form of a cross-head, vertically movable within suitable guides 35 secured to the side members of the frame 5. This cross-head includes a pair of arcuate shaped yokes 36 arranged one above the other and provided with radially disposed set screws 37, serving as centering stops for the cell-containers and adapted to be adjusted to such positions as to insure proper positioning of such containers upon the support 34 as the respective tamping operations are begun. As the active material is tamped into the cell-containee and the level of such material rises therein, the support 34 is moved downwardly against the influence of a counter-weight 39, carried at one end of a lever 40, suitably pivoted to the frame and connected at its other end to a link 41 which in turn is pivoted to the underneath side of the support 34. As the weight 39 is lifted during the filling operation of a cell-containee, the forward end of the lever 40 moves downwardly and is normally prevented against return movement by a suitable clutch 42. This clutch is of a well-known type, generally employed in connection with machines of the present character, which automatically acts to permit downward movement of the forward end of the lever 40 and is adapted to be actuated by a manually controlled lever 43 to release the lever 40 and permit its forward end to move upwardly under the influence of the counter-weight 39.

The feeding mechanism 12 for delivering the active material to the cell-containers as the tamping operations are being carried out includes a vertically movable support or carriage 45, which is guided in its vertical movement by a pair of guides 46, suitably connected to the side members of the frame 5, and by guide rollers 47 carried at its forward end and adapted to operate intermediate a pair of vertically disposed tracks 48 also suitably connected to the frame 5. This support

45 is provided at its forward end with an extension 50, having an opening 51 therein, through which the tamping fingers 17 are adapted to operate and through which the carbonaceous material or mix passes into cell-containers during the tamping operations. Within the opening 51 is located an inverted bushing 52, formed with a ledge, as shown, against which the upper end of the cell-containers are held in firm contact during the filling operations. Preferably the bushing is provided with an outwardly flared depending flange, as shown, which embraces the upper end of the cell-containee as the container is moved upwardly on the platform 34 into engagement with the bushing 52 where it is held in a clamped position between that bushing and the support until the completion of the tamping operation, whereupon it is lowered by depressing the forward end of the lever 40. Carried by the extension 50 is a semi-circular deflector wall 53, which is located adjacent the opening 51 and serves to direct material through that opening and into the cell-containee as such material is delivered from the feeding mechanism 12.

Journalled to one end of the support 45 is a shaft 55, to which is secured a roller 56 and to the opposite end of the support is journalled an idler roller 57, located in proximity to the opening 51 formed in the extension 50. Over the rollers 56 and 57 passes a conveyor belt 58 which is intermittently actuated through suitable means, hereinafter more particularly described, for delivering active material or mix to the cell-containers during the tamping operations, such material or mix being supplied from a suitable hopper 59 mounted upon the support 45 and located above the upper reach of the conveyor belt 58 in a spaced relation thereto. By reason of the fact that the hopper 59 is located above the conveyor belt and is spaced with respect to the upper reach thereof, the material is transferred from the hopper through the space afforded between the front end of such hopper and said upper reach. Directly in front of the opening through which the material is carried from the hopper, is located a transversely disposed scraper 60, the opposite ends of which are held in suitable brackets 61 by set screws, as shown, whereby the scraper may be adjusted vertically so as to vary the distance between the lower edge thereof and the upper reach of the conveyor belt. By adjusting the scraper 60 vertically within the brackets 61, the depth of the layer of active material or mix carried by the upper reach of the conveyor belt may be varied with the result that the rate at which such material is delivered to the cell-containers may be correspondingly varied. Once the scraper has been so adjusted that the material is delivered at a rate which is sufficient to take care of the requirements of the tamping

mechanism, the scraper may be permanently secured in place until an adjustment is again required, as when, for example, the consistency of the active material or mix is changed.

The driving mechanism for the conveyor belt includes a ratchet wheel 62 carried by the shaft 55 upon which the roller 56 is mounted, the ratchet wheel being adapted to co-operate with a pawl 63, pivotally connected to the side of a gear 64, loosely mounted upon the shaft 55. Meshing with the gear 64, is a reciprocating rack 65, slidably mounted within suitable guides or brackets 66 secured to the frame 5, the rack being connected at its upper end to a link 67 which is connected to an oscillatory lever 68 pivoted at one end to the frame 5, as shown at 69, and pivotally connected at its other end to the pitman rod 10', as shown at 70. It will be appreciated that as the rack 65 is reciprocated, the roller 56 is intermittently rotated, with the result that the conveyor belt 58 is likewise intermittently moved. If desired, a belt tightener 45 may be provided for the conveyor belt 58, a suitable tightener being herein shown as including a pair of adjustable arms 71, pivotally connected to opposite sides of the support 45 and carrying at their outer ends an idler roller 72 over which the lower reach of the conveyor belt operates.

As previously stated, the cell-container gradually moves downwardly as it is being filled during the tamping operation, such downward movement of the cell continuing so long as active material or mix is being transferred into the same from the hopper 59. Also, the feeding mechanism 12 moves downwardly, under the influence of gravity, however, at the same rate of speed as the cell-container, the gasket 52 being all the while maintained in firm contact with the upper edge of the container. The downward movement of the cell container and of the feeding mechanism, during the tamping operation are taken advantage of in the machine embodying this invention to limit the filling of the container to a predetermined level, and this is accomplished by discontinuing the feeding of the active material or mix to the container when such predetermined level is reached. Stopping of the feeding means is automatically accomplished by pawl-releasing means for rendering the pawl 63 inoperative, although the gear 64 carrying that pawl may continue to operate. This pawl-releasing means includes a lever 74 which is pivotally connected intermediate its ends to the frame 5 and is provided at its upper end with a foot 75, adapted to engage an outwardly projecting pin 76 carried by the pawl 63, as the feeding mechanism 12 reaches a predetermined point in its downward movement. To the opposite end of the lever 74, is pivotally connected a link 77 which, in turn, is

connected to a lever 78, secured to a transverse shaft 79, journalled in suitable bearings 80 secured to the side members of the frame 5. One end of the shaft 79 is connected to an arm 81, to the outer end of which is connected one end of a tension spring 82, the other end of such spring being secured to one of the side members of the frame 5. Also secured to the shaft 79 is a yoke-shaped tripping member which includes a pair of diverging fingers 83 and 84, adapted to co-act with a tripping pin 85, carried by a sleeve 86, secured to a rod 87 which is movable vertically with the cell-container support 34, the rod 87 being mounted upon an arm 88, which is secured at one end to such support. The other end of this arm projects upwardly and is provided at its upper end with an adjustable contact member 89 adapted to maintain engagement with the rear end of the support 45 as the feeding mechanism moves downwardly. Preferably, the arm 88 is reinforced by an angular brace 90, one end of which is connected to the link 41 and the other end of which is connected to the arm, as shown at 91, the brace 90 being in turn reinforced by a connecting member 92, one end of which is connected to the link 41 and the other end of which is connected to the horizontal portion of the brace 90.

In operation the carbon rods, not shown, such as are commonly used as the central electrodes of battery cells, are inserted between the gripping fingers 28 of the electrode holding device, while the cell-container support 34 is in a lowered position. These carbon electrodes may be inserted without necessitating the stopping of the machine, as will be readily understood, and will be gripped by the fingers 28 with sufficient force to hold them in place preparatory to the tamping operations. After inserting a carbon electrode, the operator places a cell-container upon the support 34 while such support is in its lowermost position and then releases the friction clutch 42 by lifting the hand lever 43. The releasing of the clutch 42 permits the weight 39 to move the support 34 upwardly, whereupon the top of the cell-container engages the gasket 52 and the contact member 89 engages the rear of the support 45. However, as the container is further lifted by the weight 39 the support 45 is lifted from the transverse supports 94, which are secured to the frame 5 and upon which the support 45 rests when the feeding mechanism is in its lowermost position. Upward movement of the support 45 is limited as the forward end thereof moves into engagement with the lower end of the foremost of the relatively slidable members 95 entering into the brake mechanism 42 and serving as an extensible connection between such lever and the frame 5. As the cell-container approaches filling position, the pin 85

engages the arm 84, whereupon the shaft 79 is rotated against the influence of the tension spring 82 and at about the time the container reaches its uppermost position, the spring 82, by reason of its being moved from its position shown in Figure 8 across dead center of the shaft 79, serves to further rotate such shaft with a snap action, whereupon the foot 75 is quickly moved out from beneath the pin 66 permitting the pawl 63 to drop into engagement with its associated ratchet wheel 62. Upon engagement of the pawl 63 with the ratchet wheel 62, an intermittent driving connection is established between the reciprocating rack 65 and the roller 56, with the result that the upper reach of the endless conveyor or belt 58 is moved intermittently along its path of travel. As the conveyor belt is so moved, active material or mix is transferred from the hopper 59 and deposited at the discharge end of the conveyor through the opening 51 and into the cell-container, the upper end of which is seated against the gasket 52. The material which is thus transferred to the container drops by gravity to the bottom thereof and is tamped into a compact mass about the carbon electrode by the tamping fingers 17 as they revolve about such electrode and at the same time undergo vertical reciprocation. As the material entering the container from the conveyor 58 is tamped down by the tamping fingers 17, such container, together with the support 34, is forced downwardly against the influence of the weight 39 and the feeding mechanism 12, as a whole, is moved downwardly by gravity, thus keeping the upper end of the container in firm contact with the gasket 52, it being understood that the gripping action of the compacted material upon the carbon rod is sufficient to overcome the gripping action of the electrode gripping fingers 28, with the result that the carbon rod is gradually removed from between the gripping fingers as the container descends. Downward movement of the support 34 and feeding mechanism 12 results in a corresponding downward movement of the arm 88 with which is associated the tripping pin 85, with the result that such pin is moved into engagement with the trip arm 83. After such engagement is established, further downward movement of the tripping pin 85, resulting from corresponding downward movement of the support 34, will cause the shaft 79 to partially rotate against the influence of the tension spring 82. However, as the spring 82 moves across dead center of the shaft 79, such shaft is further rotated with a quick snap action, which causes the foot 75, carried by the lever 74 which is actuated by the shaft 79, to move into a position directly beneath the pin 66 carried by the pawl 63. As the tamping operation is continued and the feeding mechanism is further lowered, the

foot 75 serves to lift the pawl 63 to inoperative position, whereupon operation of the feeding mechanism is discontinued, with the result that the transferral of material or mix to the container is stopped, such automatic stopping of the feeding mechanism being effected immediately prior to such time as the support 34 reaches the transverse supporting members 94. Upon discontinuing the feeding operation, the operator depresses the forward end of the lever 40, with the result that the support 34 is moved downwardly to such an extent as to permit the container with its packed contents to be readily removed from the support, the feeding mechanism being permitted to rest upon the transverse supports 94. After removing the container, with respect to which the tamping operation has been carried out as described, another carbon rod is inserted between the gripping fingers 28 and another container is placed upon the support 34, whereupon the friction clutch 42 is released to permit the support 34, together with the container and the feeding mechanism 12, to be moved into tamping position, the feeding mechanism being set into operation at or about the time the container reaches its uppermost position as previously described.

Although only one form of the invention is herein shown and described, it will be understood that various changes may be made without departing from the spirit of the invention or the scope of the following claims.

What is claimed is:

1. In a tamping machine for dry cells, a tamping head, a vertically movable support adapted to support a cell-container in tamping position and adapted to descend as the tamping operation is carried out, a vertically movable feeding mechanism for delivering mix to the container to be acted upon by said tamping head, said feeding mechanism being adapted to descend as said support descends and including a conveyor for transferring mix to the container during the tamping operation.
2. In a tamping machine for dry cells, a tamping head, a vertically movable support adapted to support a cell-container in tamping position and adapted to descend as the tamping operation is carried out, a vertically movable feeding mechanism for delivering mix to the container to be acted upon by said tamping head, said feeding mechanism being adapted to descend as said support descends and including a conveyor for transferring mix to the container during the tamping operation, operating means for said conveyor and means for discontinuing the operation of said conveyor whereby transfer of mix to the container is stopped.
3. In a tamping machine for dry cells, a tamping head, a vertically movable support adapted to support a cell-container in tamping

ing position and adapted to descend as the tamping operation is carried out, a vertically movable feeding mechanism for delivering mix to the container to be acted upon by said tamping head, said feeding mechanism being adapted to descend as said support descends and including a conveyor for transferring mix to the container during the tamping operation, operating means for said conveyor, and automatically actuated stopping mechanism for rendering said operating means ineffective at such time as the mix reaches a predetermined height in the container.

15 4. In a tamping machine for dry cells, a tamping head, a vertically movable support adapted to support a cell-container in tamping position and adapted to descend as the tamping operation is carried out, a vertically movable feeding mechanism for delivering mix to the container to be acted upon by said tamping head, said feeding mechanism being adapted to descend as said support descends and including a conveyor for transferring mix to the container during the tamping operation, operating means for said conveyor, and automatically actuated stopping mechanism for rendering said operating means ineffective at such time as the mix reaches a predetermined height in the container, and depending for its operation upon the vertical movement of said feeding mechanism.

5. In a tamping machine for dry cells, a tamping head, a vertically movable support adapted to support a cell-container in tamping position and adapted to descend as the tamping operation is carried out, a vertically movable feeding mechanism for delivering mix to the container to be acted upon by said tamping head, said feeding mechanism being adapted to descend as said support descends and including a carriage, a hopper carried by said carriage, a belt conveyor associated with said carriage and having its upper reach located beneath said hopper and adapted to transfer mix from said hopper to the container.

6. In a tamping machine for dry cells, a tamping head, a vertically movable support adapted to support a cell-container in tamping position and adapted to descend as the tamping operation is carried out, a vertically movable feeding mechanism for delivering mix to the container to be acted upon by said tamping head, said feeding mechanism being adapted to descend as said support descends and including a carriage, a hopper carried by said carriage, a belt conveyor associated with said carriage and having its upper reach located beneath said hopper and adapted to transfer mix from said hopper to the container, and scraping means for removing excess mix from said conveyor whereby

the quantity of mix delivered to the container per unit of time may be predetermined.

7. In a tamping machine for dry cells, a tamping head, a vertically movable support adapted to support a cell-container in tamping position and adapted to descend as the tamping operation is carried out, a vertically movable feeding mechanism for delivering mix to the container to be acted upon by said tamping head, said feeding mechanism being adapted to descend as said support descends and including a carriage, a hopper carried by said carriage, a belt conveyor associated with said carriage and having its upper reach located beneath said hopper and adapted to transfer mix from said hopper to the container, and scraping means for removing excess mix from said conveyor whereby the quantity of mix delivered to the container per unit of time may be predetermined, driving means for intermittently operating said conveyor and including a pawl and ratchet device.

8. In a tamping machine for dry cells, a tamping head, a vertically movable support adapted to support a cell-container in tamping position and adapted to descend as the tamping operation is carried out, a vertically movable feeding mechanism for delivering mix to the container to be acted upon by said tamping head, said feeding mechanism being adapted to descend as said support descends and including a carriage, a hopper carried by said carriage, a belt conveyor associated with said carriage and having its upper reach located beneath said hopper and adapted to transfer mix from said hopper to the container, and scraping means for removing excess mix from said conveyor whereby the quantity of mix delivered to the container per unit of time may be predetermined, driving means for intermittently operating said conveyor and including a pawl and ratchet device, and automatically actuated releasing means for rendering said pawl and ratchet device ineffective whereby transfer of mix to the container is stopped.

9. In a tamping machine for dry cells, a tamping head, a vertically movable support adapted to support a cell-container in tamping position and adapted to descend as the tamping operation is carried out, a vertically movable feeding mechanism for delivering mix to the container to be acted upon by said tamping head, said feeding mechanism being adapted to descend as said support descends and including a carriage, a hopper carried by said carriage, a belt conveyor associated with said carriage and having its upper reach located beneath said hopper and adapted to transfer mix from said hopper to the container, and scraping means for removing excess mix from said conveyor whereby the quantity of mix delivered to the container per unit of time may be prede-

terminated, driving means for intermittently operating said conveyor and including a pawl and ratchet device, and automatically actuated releasing means for rendering said pawl and ratchet device ineffective whereby transfer of mix to the container is stopped at such time as the mix reaches a predetermined height in the container and depending for its operation upon the downward movement of said feeding mechanism.

10. In a tamping machine for dry cells, a tamping head, a vertically movable support adapted to support a cell-container in tamping position and adapted to descend as 15 the tamping operation is carried out, a vertically movable feeding mechanism for delivering mix to the container to be acted upon by said tamping head, said feeding mechanism being adapted to descend as said 20 support descends and including a conveyor for transferring mix to the container during the tamping operation, operating means for said conveyor, and automatically actuated stopping mechanism for rendering said 25 operating means ineffective at such time as the mix reaches a predetermined height in the container, and depending for its operation upon the downward movement of said feeding device to stop the conveyor and upon 30 the upward movement of said feeding mechanism to start the conveyor.

In testimony whereof, I have affixed my signature to this specification.

OTTO KARL REINHARDT.
